UNITED STATES PATENT OFFICE.

WILLIAM T. FISK, OF DETROIT, MICHIGAN.

ILLUMINATED LICENSE-NUMBER.

1,095,321.

Specification of Letters Patent.

Patented May 5, 1914.

Application filed October 29, 1912. Serial No. 728,520.

To all whom it may concern:

Be it known that I, WILLIAM T. FISK, a citizen of the United States of America, residing at Detroit, in the county of Wayne 5 and State of Michigan, have invented certain new and useful Improvements in Illuminated License-Numbers, of which the following is a specification, reference being had therein to the accompanying drawings.

10 This invention relates to an illuminated license number for vehicles and more especially to means for displaying the license number of a vehicle at either end thereof, both in daylight and at dark.

15 The invention consists in the matters hereinafter set forth and pointed out in the appended claim.

20 In the drawings, Figure 1 is a view, partially in elevation and partially in section of a device that embodies features of the invention; and Fig. 2 is a view in front elevation thereof.

25 Referring to the drawings, a bracket 1 is secured at one end adjustably in a supporting clip 2 which may be turned into a plane whereby the bracket is held in upright position when the supporting member is fastened on an axle or horizontal part indicated at 3, or may be made to hold the 30 bracket in upright position when fastened to an upright member of the vehicle.

35 A casing 4 of suitable exterior design is yieldingly supported on the bracket by a socket 5 sliding on the upright arm. To prevent vibration the socket 5 rests on a spring 6 with a recoil spring 7 encircling the bracket above it, check nuts 8 being used to regulate the compression of the springs. The interior face of the casing is fitted as 40 a reflector, or a separate reflector may be inserted therein in order to throw the rays of a lamp 9 either electrical or not as desired, through the front of the casing.

45 A frame 10 is adapted to frictionally engage and interlock with the open end of the casing. The frame is ornamental in design and is provided with an inner holder 16 which is "L"-shaped in cross section with the vertical flange thereof provided 50 with a bead 17 that engages the inner edge of the frame and adds rigidity to the same.

An opaque plate 11 is removably mounted in the holder against the vertical flange thereof and said plate is cut away, as at 12 to provide letters, figures or other appropriate design. A sheet 13 of a translucent material and of a color in contrast with that of the outer plate 11 is removably secured in the holder 16 at the back of the plate 11. A transparent plate 14, of any preferred color, backs the translucent plate 13, all three plates being maintained in position by a stop 15 in close sliding engagement with the frame 10. The stop 15 is "L"-shaped in cross section and the vertical flange 65 thereof engages and retains the plates within the holder. As a result of this construction, an illuminated license number is obtained which may be secured at either end of the vehicle to either an upright or horizontal portion thereof and which when so secured shows the design or number clearly either in daylight or when illuminated for night use.

Obviously, changes in the details of construction may be made without departing from the spirit of my invention and I do not care to limit myself to any particular form or arrangement of parts.

What I claim is:—

50 In an illuminated license number for vehicles, a reflector, a frame carried thereby, a holder arranged in said frame and having a vertical flange provided with a bead engaging the inner edge of said frame, an opaque sign plate arranged against the vertical flange of said holder and having openings therein in the form of characters, a translucent plate arranged against the back of said opaque plate, a transparent plate arranged against the back of said translucent plate, and a stop detachably mounted in said holder and having a vertical flange engaging said transparent plate to retain all of said plates within said 95 holder.

In testimony whereof I affix my signature in presence of two witnesses.

WILLIAM T. FISK.
